Filed July 31, 1968, Ser. No. 12,980

Term of patent 14 years

Int. Cl. D3—99

U.S. Cl. D87—5

FIG. 2.

FIG. 3.

FIGURE 1 is a front perspective view of a rigid backpack, showing my new design;

FIGURE 2 is a top plan view of the rigid backpack.

FIGURE 3 is a bottom view of the rigid back pack.

FIGURE 4 is an exploded perspective view of the rigid backpack as viewed from the rear or reverse side of FIGURE 1.

FIGURE 5 is a side elevation of the rigid backpack as viewed from the right side of FIGURE 1.

The dominant features of the design reside in the full line portions of the drawing. The conventional shoulder straps shown by broken lines in FIG. 1 have been omitted from FIGS. 2-5 for convenience of illustration.

I claim:

The ornamental design for a rigid backpack, as shown and described.
